US00D896395S

(12) **United States Design Patent** (10) **Patent No.:** **US D896,395 S**
(45) **Date of Patent:** **** Sep. 15, 2020**

(54) **KNEE BRACE MASSAGER**

(71) Applicant: **Raymond Hsu**, Shenzhen (CN)
(72) Inventor: **Raymond Hsu**, Shenzhen (CN)
(**) Term: **15 Years**
(21) Appl. No.: **29/673,390**
(22) Filed: **Dec. 14, 2018**
(51) LOC (12) Cl. **28-03**
(52) U.S. Cl.
USPC **D24/215**; D24/200

(58) **Field of Classification Search**

USPC ..... D24/133, 200, 209, 211, 212, 213, 214, D24/215, 188-192, 206-207; D32/35, D32/40; D30/160; D2/901; D29/120.1, D29/120.2, 121.1, 121.2, 100, 101.1, D29/101.2, 101.3, 101.4, 101.5, 122 CPC A61H 2201/1253; A61H 23/0263; A61H 7/00; A61H 35/006; A61H 7/002; A61H 7/003; A61H 7/005; A61H 2205/022; A61H 2201/1692; A61H 7/001; A61H 7/004; A61H 7/007; A61H 7/008; A61H 15/00; A61H 15/0078; A61H 15/0085; A61H 2015/0007; A61H 2015/0042; A61H 2015/005; A61H 2015/0071; A61H 39/002; A61H 2201/10; A61H 15/0092; A61H 2201/0153; A61H 2015/0014; A61H 39/04; A61H 2201/1671; A61H 2205/102; A61F 13/38; A61F 2005/0172; A61F 5/0109; A61F 5/0123; A61F 13/085; A61F 2002/30024; A61F 2002/5055; A61F 2002/5056; A61F 2002/7818; A61F 2002/785; A61F 2005/0137; A61F 2005/0169; A61F 7/007; A61F 2007/0225; A61N 1/18; A61N 2007/0034; A61N 2005/0644; A61N 2005/0662; A61N 5/0616; A61N 1/0456; A61N 1/322; A61N 2005/0654; A61N 2005/0645; A61N 5/0613

(57) **CLAIM**

The ornamental design for a knee brace massager, as shown and described.

DESCRIPTION

FIG. 1 is a perspective view of a knee brace massager;

FIG. 2 is a side view thereof;

FIG. 3 is a side view opposite that of FIG. 2 thereof;

FIG. 4 is a top view thereof;

FIG. 5 is a bottom view thereof;

FIG. 6 is a back view thereof; and,

FIG. 7 is a front view thereof.

The drawings and descriptions represent the left side embodiment. The claim is also for a mirror image right side embodiment.

1 Claim, 7 Drawing Sheets
